UNITED STATES PATENT OFFICE.

DANIEL B. REPLEGLE, OF BERKELEY, CALIFORNIA.

VACUUM-CLEANER HOSE-PIPE.

1,293,926.

Specification of Letters Patent. Patented Feb. 11, 1919.

Application filed June 5, 1916. Serial No. 101,697.

To all whom it may concern:

Be it known that I, DANIEL B. REPLEGLE, a citizen of the United States, residing at Berkeley, in the county of Alameda and State of California, have invented a new and useful Vacuum-Cleaner Hose-Pipe, of which the following is a specification.

This invention relates to hose-pipes suitable for use in vacuum cleaning, and has for its objects, to render such hose-pipes a greater flexibility than heretofore attained, to suitably attach fiber nipples to such hose-pipes and render them more serviceable generally.

To these ends the invention consists of the construction and arrangement of parts set forth herein and illustrated in the accompanying drawing in which—

Figure 1 is a view of an end of hose pipe constructed according to my invention, the covering being partly removed to show interior construction.

Fig. 2 is a cross section showing the details of attachment of a fiber nipple.

Fig. 3 is a detail view of a ferrule used in attaching the fiber nipple.

Similar characters of reference designate like and corresponding parts in the several views.

Referring to the drawing, 1 designates a helical wire forming the skeleton of the body of my hose pipe. This is covered by a previously gummed fabric, 2, made impervious to air by a coating of rubber on at least one of its sides. This fabric is preferably applied by cutting into strips, arranging plaits or folds 3 longitudinally thereof, then wrapping so that the exteriorly exposed gummed edge 4 is covered or lapped over by the interiorly disposed gummed edge 5; thus making a continuous sealed joint helically wound about the wire frame 1.

A strong soft braiding 6 is then applied covering the fabric 2, and a fine finishing braiding 7 is applied as an outside cover. A nipple 8 made of fiber or similar material must be attached before the hose is usable. This is done by these particular means. An end 9 of the nipple 8 is interiorly screw-threaded oppositely to the spiral of the wire frame 1. The end 9 is then

expanded by steaming or soaking, which process may require several hours of time.

In practice, I procure what is commercially known as vulcanized fiber tubing made from cotton rags. The kinds made from wood pulp are not so strong and reliable. The thickness of the wall of the tubing should be in the neighborhood of three to five per cent. of the entire diameter of the tube, so that the circumferential expansion, when soaked, will be a fair approach to the thickness of the wall.

This tubing is sawed into lengths as desired, or it may be cut on a lathe, so that nurling of the outside surface, as well as threading of the interior, may be performed with once handling. The pieces are now ready for expansion, which may be effected by setting them in shallow water to a depth required to soak the threaded end to a little beyond the threaded portion. When the portion soaked has become soft and pliable, it is ready to be attached.

A ferrule 11 is now inserted into the end of a cut off piece of hose body so that it will lie against and support the wire frame from crushing in by outside pressure. A rim 12 of said ferrule 11 will cover the cut ends of braiding threads and projections or ears 13 hook between coils of wire to anchor the same firmly into the end of the cut off hose body. After this is placed the expanded end 9 of nipple 8, with or without cement applied, is screwed over the braidings compressing them closely against the wire coil 1, which screwing action tends to reduce the diameter of the coil and drive it firmly against the curved surface of the ferrule 11. Any attempt to unscrew same, as is apparent, will tend to increase diameter of the coil and increase the anchoring effect. As the nipple end dries and contracts to normal diameter, it is still more tightly drawn, compressing the fabric and braidings so tightly as to make an air proof joint as well as permanently securing said nipple to the hose body end.

When using the hose, of course both ends are secured into a nipple as explained especially when the same is to be applied to a movable vacuum cleaner. Hose thus constructed has not only a very flexible but an

extensible and contractible body so that it is easily manipulated when vacuum cleaner tools are used in connection with it. Details of construction may be varied without departing from my invention.

What I claim by patent is:

1. In a flexible hose, an interior rigid coil, a rubber coated fabric with edges sealed, covering said coil, braidings covering said fabric, a ferrule, having ears hooking into said coil and bracing the interior of said coil and a nipple having a contracting end threaded oppositely to said coil and secured over the end of coil, fabric and braiding, compressing same against the said ferrule.
- 10 2. In a flexible hose having skeleton wire coil body with fabric and braiding covering the same, a nipple having an expansible interior threaded end, said end being contracted over the end of the body of the hose, the threads of said end spiraling oppositely to said wire coil.
- 15 3. In a flexible hose, a wire coil skeleton, a gummed fabric and a braiding covering the same, an interior ferrule secured to an end of said coil, and a threaded nipple made of hygrometric material having an expansible end contracted over the end of said coil and clasping the coverings and coil aforementioned against the ferrule in the interior of the coil.
- 20 4. In a flexible hose, a wire coil skeleton,

a suitable air tight fabric covering said coil, means within an end of said coil for making the end rigid; and a fiber nipple, internally threaded spirally opposite to said wire contracted over said end.

5. In a flexible hose end, a coiled wire skeleton, an interior supporting ferrule, an exterior air tight fabric covering; and a nipple made of hygrometric material, contracted over said end.

6. In a flexible hose end, a coiled wire skeleton, an interior supporting ferrule, an exterior air tight fabric covering; and a nipple made of hygrometric material, having an end internally threaded oppositely to the coils of said wire, contracted on said end.

7. A flexible hose comprising a skeleton coil, an air-proofed pliable fabric covering said coil, and a nipple of hygrometric material contracted on an end thereof.

8. A vacuum cleaner hose comprising an interior non-collapsing coil, an air-proofed pliable fabric covering the same, an end nipple of hygrometric material contracted on an end thereof and means for supporting the interior coil against the contraction of said nipple.
